CLAIM

The ornamental design for a display screen or a portion thereof with a graphical user interface, as shown and described.

DESCRIPTION

The FIGURE is a front view of a display screen or a portion thereof with a graphical user interface, showing our new design.

The outermost broken lines illustrate a display screen or portion thereof and form no part of the claimed design. The

(Continued)

remaining broken lines, illustrating portions of the graphical user interface, form no part of the claimed design.
